UNITED STATES PATENT OFFICE.

WILLIAM F. ROEHLIN, OF ROCHESTER, NEW YORK.

APPARATUS FOR AND METHOD OF PRINTING MATERIALS.

Application filed January 17, 1923. Serial No. 613,147.

To all whom it may concern:

Be it known that I, WILLIAM F. ROEHLIN, a citizen of the United States, residing at Rochester, in the county of Monroe and 5 State of New York, have invented certain new and useful Improvements in Apparatus for and Methods of Printing Materials; and I do hereby declare the following to be a full, clear, and exact description of the 10 same, reference being had to the accompanying drawings, forming a part of this specification, and to the reference numerals marked thereon.

This invention relates to apparatus for 15 and methods of marking or printing materials and more particularly for producing figure or pattern effects on cloth, leather and other fabrics and materials. One object of the invention is to provide a simple, practical and efficient apparatus and method for 20 producing lines, figures, designs and the like on plain or pile cloth and other materials. Another object is to provide an advantageous method for accomplishing the above 25 results by a continuous and efficient form of printing operation comprising the simultaneous application of heat to the material to facilitate the penetration and setting of the ink or other printing medium therein. 30 Still a further object is to provide a simple and practical apparatus for carrying out such a method rapidly and efficiently with a minimum of labor. To these and other ends the invention resides in certain improvements 35 and combinations of parts all as will hereinafter be more fully described, the novel features being pointed out in the claims at the end of the specification.

In the drawings:

40 Figure 1 is a sectional elevation from front to rear of an apparatus embodying the present invention;

Figure 2 illustrates a pile fabric printed with the apparatus; and

45 Figure 3 is an enlarged sectional view on the line 3^a—3^a in Figure 2.

Similar reference numerals throughout the several views indicate the same parts.

The present invention comprises a method 50 for printing or simultaneously printing and goffering material by an efficient printing operation comprising the heating of the material during the impression to cause the ink or other printing medium to thoroughly 55 penetrate and become quickly set in the material, and also for accomplishing this re-

sult in a progressive or continuous manner, as, for example, by the employment of a continuously rotating printing roller or cylinder thereby eliminating the difficulty, labor 60 and unsatisfactory results attendant upon the piecing together or registering of successive partial impressions as heretofore practiced. The invention comprises also an advantageous apparatus for carrying out this 65 method which latter is best explained in connection with the following description of the apparatus.

Referring to the drawings there is shown in Figure 1 one of a pair of spaced side 70 standards 5, connected by tie rods 6 and forming the main frame of the machine. At 7 on each standard is a bracket supporting a bearing 8 and the spaced bearings 8 rotatably support the end trunnions of a 75 hollow printing roller 9 preferably dipping as shown into a reservoir or pot 10 containing ink or other coloring or printing medium.

The printing roller 9 preferably has its 80 surface formed to represent lines, figures or a pattern to be impressed on the work as exemplified in Figure 2, and this is accomplished in the present instance by engraving such pattern in intaglio on the roller 85 surface, although it is to be understood that other forms of impression surface may be employed. At 11 is a doctor bearing upon the roller surface where it emerges from the ink for removing the ink from the relief portions of the roller surface corresponding to portions such as 13 of the pattern, Figure 2, but leaving the ink in the depressed portions of the surface corresponding to the elements 14 of the pattern shown in Figure 2. The 90 printing roller is preferably provided with means for positively rotating the same, as, for example, the pulley 15. The roller also has conducting means or pipes 16 communicating at its ends with its interior, as, for 100 example, through the hollow form of trunnion well known in the art for this purpose, and a continuous flow of a cooling medium such as water is maintained by any suitable means through the pipes 16 and roller for 105 maintaining the latter in a relatively cool state for a purpose which more fully appears hereafter.

The material to be printed is illustrated 110 in the present instance as a web 17 of plush, velvet or other pile cloth which is fed in the direction indicated by the arrow with its

face or pile side in contact with the printing roller 9, the web being supplied from a roll 18 rotatably supported by a bracket 19 at the rear of the machine over guide rolls 5 20 and to a winding up roller 21 carried by a bracket 22 in front of the machine and rotated by any suitable means (not shown). A platen means is provided for engagement with the back of the material for 10 pressing the face or pile side thereof into contact with the printing roller and also for heating the material while in contact with the printing roller to facilitate the penetration of the ink or other coloring or print- 15 ing medium into the material and the setting of such medium. This platen means may obviously have various forms being preferably however, as in the present instance, a hollow roller 23 having trunnions jour- 20 nalled respectively in bearings 24 adjustable vertically on guide-ways 25 on the side stand- ards. These bearings are preferably sup- ported by threaded spindles 26 engaged in correspondingly threaded bores in heads 27 25 circumferentially grooved as at 28 and pro- vided with adjusting hand wheels 29 for rotating the same. Heads 27 are supported by engagement with the grooves 28 thereof of the end 30 of a lever 31 pivoted on the 30 upper cross-rod 6 and it is apparent that by rotating hand wheel 29 the corresponding bearing 24 may be raised or lowered to adjust the corresponding end of the platen roller from or toward the printing roller 35 to correct the alignment or vary the pressure. Lever 31 is pivotally connected as at 32 with a link 33 pivotally connected at its opposite end 34 with a lever 35 ful- crumed on one of the cross rods 6, having 40 a long arm extending forwardly of the machine and provided with adjustable weight means 36. It is apparent from this construction that the weight means 36 serve to press the platen roller against the mate- 45 rial at the portion of contact of the latter with the printing roller, the rotation of which serves to feed the web of material between itself and the platen roll 23 which is thus frictionally driven. The platen 50 roller may however be positively driven if so desired.

The platen roller is heated for the purpose specified preferably by conducting means such as pipes 37 communicating 55 through hollow trunnions of the platen roller with its interior for supplying a continuous flow of a suitable heating medium as for example hot water or steam. By regulating the supply of heating medium 60 the temperature of the platen may be controlled and the desired degree of heat thus applied to the material during the contact of the latter with the printing roller. 65 Such application of heat would tend to also heat the printing roller and thus injuriously

affect the ink or other printing medium, as, for example, by drying or baking the same or in some cases dissolving the printing medium, depending upon its character. This is overcome in the present invention by 70 provision of the means described for maintaining the printing roller at the desired degree of coolness so that, while the desired heating effect is obtained in the material and in the ink absorbed thereby, the printing 75 roller is nevertheless maintained at the desired efficient printing temperature.

By suitable selection of the depth and character of the engraved depressions in the printing roller, and the degree of pressure of the platen roller thereagainst, a goffering operation may obviously be accomplished simultaneously with the printing, as well understood in the art, and particularly at the portions of the material 85 impressed between the platen and the edges of the engraved depressions which tend to break and flatten the pile. Where the ink is applied the pile is permanently laid in the manner indicated at 38, Figure 3. The 90 printing and goffering effects may of course be varied by employing a platen roller engraved to correspond or mate with the engraving of the printing roller if so desired and the degree of goffering effect may 95 obviously thus be increased.

As apparent from the above description the material is printed by a progressive or continuous method comprising the simultaneous application of heat to the material 100 without however heating the printing roller or the ink while carried thereby. The ink is carried in the depressions of the printing roller which deliver it to the material at portions thereof not subjected 105 to pressure because of the depressions in the printing surface. The ink is thus allowed to penetrate the material at an incompressed portion of the latter which is also subjected to the favorable action of heat from the platen roll under which thorough penetration of the material and quick setting of the ink is accomplished. While the method has been specifically described in connection with a pile fabric 110 it is not by any means limited to this class of work but may be also be employed for printing and goffering plain cloth and other materials. The method is obviously 115 practical and efficient in character and capable of being accomplished in a continuous and rapid manner yielding a better quality of work than can be economically produced by methods involving the piecing together or registering of successive partial 120 impressions as in methods heretofore practiced. The method may be carried out by simple, practical and economical apparatus such as described with a minimum of labor. The combined printing and goffering, par- 125 130

ticularly of a pile fabric affords results of a highly artistic and pleasing character.

I claim as my invention:

1. In apparatus of the character described, the combination of a printing roller, devices for applying a printing medium thereto, means for cooling said roller, a platen for the opposite side of a material to be printed, and heating means for said platen.
2. In apparatus of the character described, the combination of an engraved printing roller, inking means therefor, means for conducting heat from said printing roller to maintain the same relatively cool, a platen roller for the opposite side of a material to be printed, and means for supplying heat to said platen roller to draw and set the ink in the material.
3. In apparatus of the character described, the combination of a rotary engraved hollow printing roller, devices for applying ink thereto, means for removing ink from relieved portions thereof forming a design, conducting means for supplying a continuous flow of a cooling medium through said printing roller, a hollow rotary platen roller for the back of a material to be printed on its face by said printing roller, and conducting means for supplying a continuous flow of a heating medium through said platen roller.
4. In apparatus of the character described, the combination of an engraved roller adapt-
- ed for printing and goffering one side of a material, devices for applying a printing medium to intaglio portions of said roller exclusively, a platen roller adapted to press the material from its opposite side into printing and goffering contact with said engraved roller, and means for heating said platen roller.
5. In apparatus of the character described, the combination of an engraved hollow roller adapted for printing and goffering the pile side of a material, devices for applying a printing medium to the engraved surface of said roller, conducting means communicating with the interior of said engraved roller for supplying a continuous flow of a cooling medium thereto, a hollow platen roller adapted to press the material from its opposite side into printing and goffering contact with said engraved roller, and conducting means for supplying a continuous flow of a heating medium to said platen roller.
6. The method of printing a material consisting in progressively pressing the face side thereof against a rotary engraved and inked printing roller, applying heat to the back of the material at the portion of contact with said roller to draw and set the ink in said material and conducting heat away from said roller to maintain the latter relatively cool and thereby prevent injuriously affecting the ink on said roll.

WILLIAM F. ROEHLIN.
